J. V. LOEFFLER

MUFFLER CUT-OUT

Filed Sept. 30, 1922

John V. Loeffler,
Inventor

By Mason Tomick & Lawrence,
Attorneys

UNITED STATES PATENT OFFICE.

JOHN V. LOEFFLER, OF EVANSVILLE, INDIANA.

MUFFLER CUT-OUT.

Application filed September 20, 1922. Serial No. 591,596.

To all whom it may concern:

Be it known that I, JOHN V. LOEFFLER, citizen of the United States, residing at Evansville, in the county of Vanderburgh 5 and State of Indiana, have invented certain new and useful Improvements in Muffler Cut-Outs; and I do hereby declare the following to be a full, clear, and exact description of the invention, such as will enable 10 others skilled in the art to which it appertains to make and use the same.

The invention relates in general to means for controlling the flow of fluid from a conduit through either of a plurality of 15 branches. It more particularly concerns a so-called cut-out device for diverting, at will, exhaust gases, flowing in the exhaust pipe leading from an internal combustion engine, either through a muffler to the outer 20 air or directly to the outer air without passing through a muffler.

An object is to direct the exhaust in a perfectly straight course to the outer air when the cut-out is open, thereby eliminating 25 the back pressure caused by obstructions and crooked courses; another object is to simplify, strengthen and cheapen devices of this character.

The invention consists in the combination 30 and details of structure more specifically described hereinafter, delineated in the drawings and defined in the appended claims.

In the accompanying drawings, in which like reference characters indicate like parts 35 throughout the several views, I have illustrated one preferred embodiment of my invention of which:

Fig. 1 is a side elevation;

Fig. 2 a view, in plan, of the device below 40 the section line 2—2 of Fig. 1;

Fig. 3 is a view of a section cut on the line 3—3 of Fig. 2, viewed in the direction of the arrow;

Fig. 4 a side elevation of a detail of the 45 gate valve actuator separated from the rest of the device;

Fig. 5 is an elevation of a detachable pedal member;

Fig. 6 is a plan view of the pedal member;

Fig. 7 is an elevation of the gate valve 50 detached;

Fig. 8 is a plan view of the gate valve detached.

In the drawings, 1 indicates what is here 55 termed a valve body, and comprises a hollow pipe fitting having one inlet port 1^a

and two outlet ports 1^b and 1^c. Said body is also provided with a lug or ear 2, preferably formed integrally with said body, and perforated for the reception of a pivot bolt 60 2^a, on which a gate valve 3 is hinged. A cotter pin 2^b or other fastener may be applied to the threaded end of said bolt to retain the gate 3 against its seat. The outlet opening 1^b is at one end of a substantially straight passage leading to it from 65 the inlet port 1^a, and the valve seat is a plane and smooth surface 26,—preferably machined or ground,—so that the corresponding,—also machined or ground,—face 70 26^a of the gate valve 3 may have a tight fit therewith. The plane of the valve seat and co-engaging face of the gate valve cuts the axis of the passage leading to outlet port 1^b 75 from inlet port 1^a, obliquely, making, with the side of the passage nearest the hinge of the valve, an obtuse internal angle for a purpose that will hereinafter be revealed. Overhanging the valve seat at the side opposite the pivotal connection of the gate 80 valve there may be a lip 20 adapted to engage over the free end of the gate valve, and preferably over a projection 3^a thereon, for the purpose of holding the gate valve against the seat when acted on by the pressure of the exhaust gas tending to push it away.

For the purpose of controlling the position of the gate valve at the will of the driver a manual actuating device of simple 90 construction is provided. In the illustrated embodiment the actuating device is so disposed that the valve may be opened by the pressure of the foot of the driver of a car, and may be automatically closed upon relief 95 of that pressure. The actuating device shown comprises a slidable actuator, a guide therefor, a member on the gate valve engaged by the actuator, and a spring for closing the gate and restoring the actuator to 100 normal position.

The guide member 4 comprises a flat elongated body 4 seated in a gain 4^a formed in the face of lug 2 at one side of the pivot pin 2^a and occupying in the intended 105 use an upright position. Member 4 may be secured in place by a bolt 4^b passed through it and the lug. At each end member 4 is provided with offset slide bearings which comprise separate ears 5 and 5^a at each end, the spaces between said two sets of ears being 110 in registration or substantial axial aline-

ment and serving as guide bearings for the upright actuator. Before assemblage of guide and actuator the ears project in substantial parallel relation to permit the actuator to be moved laterally into position between them. Thereafter the ends of one or both of each pair of ears, (which are preferably composed of ductile metal) may be bent so as to embrace and confine the actuator in such manner that, while permitting an up and down slideable movement of the actuator the actuator can not be removed laterally from the slide bearings. The upper slide bearing, formed in part by lugs 5 and 5^a, is made to fit the actuator somewhat more loosely than the lower bearing in order to allow a limited lateral movement of the upper portion of the actuator for a purpose to be presently explained.

20 The actuator 6 consists of a longitudinal member guided by the described guide bearings of the guide member 4. Said actuator is provided with a transverse slot, which may be open ended and formed between parallel lugs or fingers 11, projecting from one side thereof. Upon the pivoted gate valve 3 there is a pin 3^b disposed in suitable position to enter the slot between the fingers 11 on the actuator. When the actuator is moved up or down the gate 3 is closed or opened. At its upper end the actuator 6 is provided with a detachable and adjustable button or head 7, preferably so formed as to constitute a pedal member adapted to be conveniently engaged by the foot of the driver whereby the actuator may be depressed and the gate valve opened. The button or pedal 7 may have parallel arms 8, 8' depending from its under side, between which fits a rib 6^a on one side of the upper end of actuator 6 when the pedal is secured thereto. A bolt 17 passing through hole 6^b in the actuator and between the arms 8, 8' is adapted to secure the pedal member adjustably to the upper end of the actuator. One (or both) of those portions of the actuator that are engaged by the slide bearings are of such cross sectional form as to prevent the actuator from turning about its longitudinal axis by reason of engagement with the slide bearing, which is of substantially corresponding form. As shown the actuator is rectangular in section and engages in corresponding openings in the slide bearings. The fingers 11, hitherto mentioned, engage the pin 3^b; and a catch tooth 9, with suitable notch above it, engages under the upper slide bearing (as under bent lug 5^a) whereby the actuator may be locked in lowered position. The said engagement, or interlock, between the actuator and upper bearing is permitted by the relatively loose fit of the actuator in the upper bearing as compared with the relatively snug fit thereof in the lower bearing, there

being, of course, sufficient ease of fit between the lower bearing and the part of the actuator sliding in it to allow the actuator to rock on the lower bearing as a fulcrum. The actuator tends to assume its uppermost position by reason of the elastic force of a spring, such as 12, which may have one end attached to the lug or ear of the upper slide bearing on guide member 4 and the other end attached to a projection 7^a on the actuator, the force of the spring being applied in such manner as to cause the upper end of the actuator to bear toward the curved lug 5^a so that the locking tooth 9 will engage under it when the actuator is depressed to completely open the gate valve, thereby locking the gate valve 3 open. A small lateral movement of the upper end of the actuator away from the curved lug 5^a releases the lock, whereupon relief of pressure from pedal 7 allows the actuator to resume its normal position and the gate valve to close. Any suitable stop device may be applied to limit the opening and closing movements of the valve. The opening movement may, for example, be limited by engagement of projection 10 with the lower slide bearing, and the closing movement may be limited by the upper finger 11 engaging under the upper slide bearing.

When the improved cut-out is used on a motor vehicle the discharge end of an exhaust pipe section 13 is fitted into the inlet port 1^a of the body or casing 1, and the inlet end of a section 14 leading to a muffler (not shown) is fitted into the outlet port 1^c. The ends of said sections may be secured to the body or casing 1 by any appropriate device such as set screws 13^a and 14^a. The port 1^b, as stated before, is so related to the inlet port 1^a that the passage through pipe section 13 to port 1^b is straight. The port 1^c is offset from the axis of the straight passage between ports 1^a and 1^b and the passage in the body or casing 1 leading from port 1^a to port 1^c is oblique, or curved, horizontally. Should, now, the gate valve 3 be opened during the operation of the engine with which the device is associated, the exhaust gases flow along the direction of least resistance in a straight course out of the port 1^b directly into the outer air. When the gate valve 3 is closed the exhaust gases impinge upon the oblique surface of the gate valve and are deflected to the port 1^c. Thus, when the gate valve is closed it forms one wall of an oblique deflecting passage for conducting the gases to port 1^c and onward to the muffler.

In use with a motor vehicle the actuating device 6 will project through the floor of the vehicle body with the button or pedal 7 in a position convenient to the driver's foot. The construction is strong and simple. The actuator is a simple sliding mem-

ber directly connected to the gate valve, thus obviating links, levers and complicated transmission devices. The smooth faced external gate valve is unlikely to bind or jam, and provides, withal, a sufficiently tight fit to prevent escape of gas when it is closed. It is subjected to the impact of the hot gases only in the closed position and is moved entirely out of the path of the gases when open to cut out the muffler.

What I claim and desire to secure by Letters Patent is:—

1. A muffler cut-out comprising a body having an inlet and two outlet ports, a substantially straight passage between the inlet and one of said outlet ports, an oblique passage leading to the other outlet port, said outlet port at the end of the straight passage having a valve seat oblique to the axis of said straight passage, and a valve which, when closed, constitutes a portion of the wall of said oblique passage.

2. A muffler cut-out comprising a body having an inlet and two outlet ports, a substantially straight passage between the inlet and one of said outlet ports, an oblique passage leading to the other outlet port, said outlet port at the end of said straight passage having a plane exterior seat oblique to the axis of said straight passage, and a gate valve slidable on said seat; said gate valve, when closed, constituting a portion of the wall of said oblique passage.

3. A muffler cut-out comprising a body having an inlet and two outlet ports, a substantially straight passage between the inlet and one of said outlet ports, an oblique passage leading to the other outlet port, said outlet port at the end of said straight passage having a plane exterior seat oblique to the axis of said straight passage, and a pivoted gate valve slidable over said seat; said gate valve when closed constituting a portion of the wall of said oblique passage.

4. In an exhaust conduit for internal combustion engines, a body having an inlet and two outlet ports, a substantially straight passage between the inlet and one of said outlet ports, an oblique passage leading to the other outlet port; a pivot supporting lug, a plane exterior seat surrounding the outlet port at the end of the straight passage and extending over the face of said lug, said plane seat being oblique to the axis of said straight passage; and a gate valve pivoted on said lug and slidable on said seat; said

valve, when closed, constituting a portion of the wall of said oblique passage.

5. In an exhaust conduit for internal combustion engines, a body having an inlet and two outlet ports, a substantially straight passage between the inlet and one of said outlet ports, an oblique passage leading to the other outlet port; a pivot supporting lug, a plane exterior seat surrounding the outlet port at the end of said straight passage and extending over the face of the lug, said plane seat being oblique to the axis of said straight passage; a gate valve pivoted in said lug and slidable in said seat, a lip on the body adapted to hold the free end of the valve to the seat; said valve, when closed, constituting a portion of the wall of said oblique passage.

6. In an exhaust conduit having a muffler cut-out port; a pivoted gate valve for opening and closing said port; an upright bar-like actuator therefor; a pin on the valve; parallel fingers on the actuator between which said pin is engaged; a slide bearing above and below said fingers, and a spring connected to the upper bearing and to said actuator tending to close the valve.

7. In an exhaust conduit having a muffler cut-out port; a pivoted gate valve for opening and closing said port; an upright bar-like actuator therefor having a transverse slot; a pin on the valve engaging in said slot; a slide bearing above and below said slot, the upper bearing engaging the actuator loosely; a tooth on the actuator adapted to engage beneath the upper bearing; a lug on the actuator on the side opposite the tooth; a tension spring having one end attached to the upper bearing and its other end to the lug on the actuator in such position as to exert its force to lift the actuator and valve and force the toothed side of the upper portion of the actuator to press against the upper slide bearing.

8. In an exhaust conduit having a muffler cut-out port; a valve for opening and closing said port; a bar-like actuator therefor; a guide for the actuator having a slide bearing adapted to admit the actuator laterally, said slide bearing comprising lugs one at least of which is ductile and curved to confine the actuator in the slide bearing.

In testimony whereof I affix my signature.

JOHN V. LOEFFLER.
